UNITED STATES PATENT OFFICE.

JACOB WEBER, OF NEW YORK, N. Y.

WINDOW.

1,119,482.

Specification of Letters Patent.

Patented Dec. 1, 1914.

Application filed May 21, 1913. Serial No. 768,993.

To all whom it may concern:

Be it known that I, JACOB WEBER, a citizen of the Kingdom of Hungary, residing in New York, in the borough of Manhattan, 5 county and State of New York, have invented certain new and useful Improvements in Windows, of which the following is a specification.

This invention relates to a window in 10 which the sashes are pivoted to swing inward into horizontal position for a convenient cleaning of the outside surfaces of the window panes.

In the accompanying drawing, Figure 1 15 represents an end-elevation of my improved window, Fig. 2 is a vertical transverse section of the same on line 2—2, Fig. 1, showing the sashes in closed position, Fig. 3 is also a vertical transverse section, showing 20 the lower sash in inwardly-lowered position for cleaning the same, Fig. 4 is a vertical transverse section on line 4—4, Fig. 5, drawn on a larger scale, and Fig. 5 is a detail horizontal section on line 5—5, Fig. 4.

25 Similar letters of reference indicate corresponding parts throughout the different figures of the drawing.

Referring to the drawing, *c* represents the casing, *a* the lower, and *b* the upper sash of 30 my improved window. The sashes are guided by three guide-strips *d*, *d*¹, *d*², of which the intermediate guide-strip is somewhat narrower than the outer and inner guide-strips *d*² and *d*. The outer guide-strip *d*² is stationary, while the lower sections of the intermediate and inner guide-strips *d*¹, *d* are detachable. The detachable portions extend somewhat above the meeting rails of the sashes and are made tapering 35 at the upper ends so as to project into V-shaped recesses of the upper portions of the guide-strips. The adjacent ends of the removable section and of the upper stationary section of the guide-strips *d*, *d*¹ are reinforced by metallic plates *d*³, which correspond in shape with the shape of the adjacent ends of the guide-strips which are attached thereto by means of fastening screws, as shown clearly in Fig. 2. To the upper 40 ends of the intermediate and inner detachable guide-strips *d*, *d*¹ are applied connecting pins *e*, which are provided at their outer ends with thumb-pieces *e*¹, disk-shaped collars *e*² adjacent to the thumb-pieces, and 45 transverse pieces *e*³ at the inner ends, said pieces passing through slots *s* in metallic

plates *e*⁴ attached to the window-casing, so that the upper ends of the detachable guide-strips *d*, *d*¹ can be quickly locked to the casing by passing the inner transverse pieces 60 through the slots of the plates *e*⁴ and then turning the pins through an angle of 90°, as shown in Figs. 4 and 5. By turning the thumb-pins back again so as to bring the thumb-pieces into vertical position, the 65 transverse piece *e*³ can readily pass through the slots *s* in the plates *e*⁴ for permitting the detaching of the guide-strips from or reattaching of the same to the casing. The lower ends of the guide-strips *d*, *d*¹ are provided 70 with reinforcing metallic plates *d*⁴ which extend into recesses *d*⁵ in the window-sill, as shown in Fig. 4, so that the guide-strips *d*, *d*¹ can be readily detached whenever desired for cleaning the sashes, by simply releasing the thumb-pins from their upper ends and lifting the guide-strips, while placed in a slightly inclined position, out 75 of the recesses in the sill.

The lower and upper sashes *a* and *b* are 80 each connected by pivots *f* to the lower ends of slide-pieces *f*¹ which are connected at their upper ends with the usual sash cords or chains *f*² that pass over pulleys at the upper end of the casing into the sash-boxes 85 in the usual manner. The sashes are provided at their side-rails with projecting pins *f*³ which enter into recesses *f*⁴ of the slide-pieces *f*¹, as shown clearly in Figs. 2 and 3, so that the sashes are held at two points on 90 the slide-pieces, namely, by their lower pivot-pins and by the side-pins *f*³ in the recesses *f*⁴. The sashes are moved with the slide-pieces between the guide-strips when raised or lowered as required. To the upper 95 meeting rail of the lower sash are applied at each side of the same slide-bolts *g*, which are guided in slotted casings *g*¹ and operated by knobs *g*². The slide-bolts *g* serve for holding the lower sash in inwardly-inclined position by engaging sockets arranged in arc-shaped guide-strips *g*³ attached to the jambs of the window-casing *c*, as shown in Figs. 2 and 3. The socketed plates *g*³ are concentric with the pivot-bolts 100 *f* of the lower sash so as to permit the placing of the lower sash into inwardly-inclined position, and form thereby an open space between the upper end of the lower sash and the lower end of the upper sash through 105 which the air may enter to the inside of the room for ventilation purposes, without raising

ing the lower or lowering the upper sash, the sash being held firmly in position against exterior wind-pressure by the slide-bolts. This forms a less objectionable 5 method of ventilation than the present mode of ventilating by opening the sashes. The lower ends of the slide-pieces f^1 are provided with metallic reinforcing socket-plates f^2 for the pivot-pins of the sashes, 10 whereby the pivotal connection between the slide-pieces and the lower and upper sashes is rendered stronger and more durable.

When it is desired to clean the sashes at 15 their inner surfaces, the intermediate and inner detachable portions of the guide-strips d and d' are removed and the lower sash then swung on its pivots into lowermost position, as shown in Fig. 3, so that the outer surface of its glass pane can be cleaned; the 20 sash is then moved into vertical position again and the inner surface cleaned. The lower sash is then raised with its slide-pieces into uppermost position and the upper sash lowered with its slide-pieces into lowermost 25 position and swung inwardly on its pivots, in the same manner as the lower sash before, then cleaned on the outer side of its pane, raised into upright position and cleaned at the inner surface of its pane, 30 and then raised again with its slide-pieces into uppermost position, after which the lower detachable portions of the intermediate and inner guide-strips are replaced in position and locked to the casing by the 35 thumb-pins engaging the slotted plates of the casing, as shown in Fig. 5. The lower and upper sashes can be locked in closed position by means of any approved fastener for the meeting rails of the sashes. Owing 40 to the facility by which the lower portions of the intermediate and inner guide-strips

are removed, whereby the lower as well as the upper sash, one after the other, can be lowered into inwardly-extending position, the cleaning of the sashes can be accomplished from the inside of the room with great facility, and then the sashes returned into their proper positions. The detachable portions of the guide-strips are then replaced in position and the sashes raised 50 and lowered in the usual manner.

By reinforcing the detachable guide-strips and the slide-pieces by means of metallic plates, to which the movable parts, thumb-pins, pivots, etc., are applied, a very strong 55 and permanent connection of the parts is obtained, so that the sashes can be operated for a considerable length of time without getting out of order and requiring repairs.

I claim:

The combination of a window casing provided with vertical guide strips having transverse recesses, slide pieces movable between said guide strips and provided with lateral slots near their upper ends, means 65 for suspending said slide pieces, a sash, pivotal connections between said sash and said slide pieces at the lower ends thereof, and studs on said sash adapted to pass through said recesses in said guide strips into said 70 lateral slots in said slide pieces when said slide pieces are in proper position for the opening of the sash and to engage said guide strips and hold the sash closed in other positions thereof.

In testimony, that I claim the foregoing as my invention, I have signed my name in presence of two subscribing witnesses.

JACOB WEBER.

Witnesses:

PAUL GOEPEL,
JOHN MURTAGH.
